LOCK MORTISER

Walter K. Taylor, Jersey City, N. J., assignor to
 American Houses, Inc., New York, N. Y., a corporation of Delaware

Application April 27, 1942, Serial No. 440,676

7 Claims. (Cl. 144—84)

This invention relates to new and improved apparatus for use primarily in connection with the manufacture of doors and the like, and adapted more specifically for use in the cutting of lock mortises, lock face mortises, and drill holes for door locks and spindles.

An object of the invention is to provide apparatus of the character described comprising essentially a work-receiving bench or table equipped with a plurality of drills and a plurality of lock mortisers, and with means for insuring the proper movement into and out of cutting position of said drills and mortisers whereby doors of standard sizes and thickness may be rapidly and cheaply prepared for the reception of locks, lock face plates, door knobs and spindles.

Other objects of the invention are to provide apparatus of the character described comprising a plurality of pivotally mounted tool-carrying elements; to provide a drill and a mortiser associated with each of said elements; to provide in connection with one of said elements a mortiser for cutting a lock mortise; to provide in connection with the other of said elements a mortiser for cutting a lock face mortise; to provide in connection with one of said elements a drill for cutting a lock hole; to provide in connection with the other of said elements a drill for cutting a spindle hole; to provide clamping means in connection with each said pivotally mounted element for insuring the proper position of the cutting tools associated therewith; to provide means in connection with the work-receiving table to properly position thereon any door of standard predetermined thickness.

Other objects of the invention will in part be obvious and will in part appear hereinafter.

The invention accordingly comprises the apparatus embodying features of construction, combination of elements and arrangement of parts, all as exemplified in the following detailed disclosure, and the scope of the application of which will be indicated in the claims.

For a fuller understanding of the invention, reference should be had to the following detailed description, taken in connection with the accompanying drawings, in which:

Figure 1 is a plan view of apparatus embodying one form of the invention; and

Fig. 2 is an enlarged vertical section of the apparatus shown in Fig. 1 taken along the line 2—2 therein.

There is an increased demand today for large numbers of relatively inexpensive houses. This demand has arisen in part from the effort of in-

dustry to provide adequate housing for its employees, and more recently from the increasing demands for adequate housing in connection with the rapid development of war industries. Prefabricated dwellings have been suggested as one answer to this housing problem. In dwellings of this type and in the cheaper type of individual dwelling construction it is customary to employ doors of standard sizes, and more specifically doors of standard thickness. This is true even where the height and width of the door employed may vary slightly with its use in the dwelling. Practically every door is provided with a lock, and the cutting of the necessary holes to accommodate the lock, the lock face plate and the spindle for the door knob has been an element of considerable cost, especially where a great number of dwellings are being erected and many thousands of doors used. This invention has for its object essentially the provision of apparatus which will facilitate the cutting of the lock mortises, lock holes, spindle holes, and lock face mortises, especially where large numbers of doors of the same thickness are to be cut.

In the embodiment of the invention shown in the drawings, 10 represents a work-receiving table. Along one edge of the table there is provided an abutment element 12 which may be, for example, an angle iron bolted or otherwise affixed to the top 14 of the table. The table top may be formed of any suitable flat element, preferably a plywood panel, as shown for example most clearly in Fig. 2. The work, i. e., the door which is to be cut, and which is shown as at 16 in Fig. 2 in dotted lines, is preferably supported above the table top 14 on spaced elements 18 to facilitate movement of the work upon the table.

The front or work-engaging edge of the table top is provided with a plurality of spaced abutment elements 20 which are positioned perpendicular to the abutment element 12, and which in connection therewith determine the position of the work upon the table. The upper portion 14 of the table is cut away, as shown most clearly in Fig. 1, in the center of the table and along the front edge thereof, as at 22, to provide a recess for the reception of the drills and mortisers employed in connection with the use of the apparatus as hereinafter explained. As is apparent also from Fig. 1, this portion of the table is free from the abutment elements 20. The cut-away portion of the table top 14 providing the recess 22 extends substantially back of the edge of the work which is to be mortised and drilled and which is in close contact with the

abutment elements 20. There may be provided at the opposite end of the table to that equipped with the fixed abutment element 12 an adjustable further abutment element 24 which may be moved into contact with the edge of the work thereadjacent and fixed in position so as to assist in holding the work in proper position upon the table. This abutment element, however, is not essential to the operation of the device. The elements 12 and 20 function adequately to insure proper positioning of the work upon the table.

Positioned beneath the table top 14 and extending beneath the recess 22 therein is a supplemental platform or table 26 adequately supported on the frame of table 10 by the arms 28. Platform 26 carries thereon two tool-supporting elements 30, 32. Element 30, the right-hand element shown in Fig. 1 and that element shown in Fig. 2, is pivoted, for example at 34, and is provided with one or more roller supports 36 traveling upon a rail 38 carried by element 30. Element 32 is similarly pivoted at 40 and is similarly provided with one or more rollers 42 riding upon rail 44 on the surface of platform 26. Elements 30 and 32 may be movable from, for example, the position shown in the drawings to a position in which the cutting tools carried thereby are in operative engagement with the door or other work 16. Each tool-carrying element 30, 32 is provided with a plurality of clamps 46 which are adapted to engage the door or other work to be cut and thus secure proper, firm positioning of the cutting tools with respect to the work.

It will be understood that the drawings show only diagrammatically the cutting devices which are to be employed in the practice of the invention. These devices are standard. Each tool-supporting element 30, 32 is provided with a drill 50 suitably mounted thereon, one drill, for example that carried by element 30, being adapted to drill the lock hole in the door, and the other drill, for example that carried by the element 32, being adapted to drill the spindle hole in the door. These drills are preferably power-driven, manually controlled, and equipped with suitable stops and controls for insuring proper cutting of the work. It is immaterial in the practice of the present invention whether the drill associated with the element 30 is adapted to cut the lock or the spindle hole, and the details of tool construction are not part of the present invention. It will be apparent to anyone skilled in the art what tool should be employed for the specified purpose and where it should be mounted on either carrier 30, 32.

Each carrier 30, 32 is equipped also with a power-driven lock mortiser 52. Here again the tool construction is not part of the present invention, and either mortiser, for example that carried by element 30, may be adapted to cut the lock mortise, and the other mortiser, for example that carried by element 32, may be adapted to cut the lock face mortise in the door. Again the selection of tool and proper positioning on the tool carrier will be obvious to those skilled in the art, and the drawing is to be understood as showing merely diagrammatically and without accurate detail, either as to tool structure or tool position, the elements herein described. It may be mentioned, however, that suitable mortisers for use in the practice of the present invention are those manufactured by the R. L. Carter Division of The Stanley Works, and known as Carter lock mortisers. While ordinarily the lock face mortise is cut with a router, it has been found that in the

practice of the present invention duplicate machines may be employed to cut the lock mortise and the lock face mortise.

In the practice of the present invention a door 5 to be cut is placed upon the elements 18 and moved into position against the abutment elements 12 and 20 with the portion of the door to receive the lock positioned over the recess 22 in the table top 14. Normally the bottom of the door 10 will rest against abutment 12. One or the other of the pivotally mounted tool-carrying carriages 30, 32 is then moved from the position shown in the drawings to a position in which the clamps 46 are adapted to engage the work 16. To insure 15 proper positioning of the carriages a stop 54 may be provided at the ends of the rails 38, 44 and when the foremost roller 36, 42 of each carriage makes contact with the stop, the carriage will be in proper position with respect to the work. The 20 clamps 46 are then affixed to the work and the operator then cuts either the lock mortise or the lock face mortise, as the case may be, and drills either the lock hole or the spindle hole, as the case may be. When the work is completed the 25 clamps are released, the carriage is swung back in the position shown in the drawings, the other carriage is moved forward into work-engaging position, and the remaining mortise is cut and the remaining hole drilled.

30 With apparatus of the type described a vast number of doors can be prepared for the reception of the lock rapidly and at little expense. While the saving in cost per door may not be great, the over-all saving in the manufacture of 35 thousands of doors is substantial.

Certain modifications of the invention will be apparent to those skilled in the art. For example, the tool-carrying elements may be mounted in other ways to be moved into and out of engagement with the work. So also, other forms of 40 work-receiving table may be employed. The work may be clamped directly to the table, for example, and the tool-carrying elements may be locked into operative position by any suitable means 45 which prevents their movement with respect to the table itself. Under these circumstances the clamps carried by the elements 30, 32 may be dispensed with. Other similar modifications in the apparatus will be obvious to those skilled in the art.

50 Since certain changes in the constructions set forth which embody the invention may be made without departing from its scope, it is intended that all matter contained in the above description or shown in the accompanying drawings shall be interpreted as illustrative and not in a limiting sense.

It is also to be understood that the following 55 claims are intended to cover all the generic and specific features of the invention herein described, and all statements of the scope of the invention which, as a matter of language, might be said to fall therebetween.

What is claimed is:

65 1. A device of the character described comprising, in combination, a fixedly positioned, work-receiving table, guide means for predeterminedly positioning work thereon, means providing a recess in said table adjacent one edge thereof, a platform positioned in part beneath the work-receiving surface of said table and underlying said recess, a plurality of tool carriers 70 movably mounted on said platform, at least one cutting tool mounted on each said carrier, each said carrier being movable between a position in

which the tool carried thereby engages the work and a position in which the tool is removed from the work, and means for fixedly positioning each carrier with respect to the work when the tool carried thereby engages the work, each said tool being movably mounted on its carrier whereby it may operate on the work when the carrier is fixed with respect thereto.

2. A device of the character described comprising, in combination, a fixedly positioned, work-receiving table, guide means for predeterminedly positioning work thereon, means providing a recess in said table adjacent one edge thereof, a platform positioned in part beneath the work-receiving surface of said table and underlying said recess, a plurality of tool carriers pivotally mounted on said platform, a plurality of cutting tools mounted on each said carrier, each carrier being movable into and out of position beneath said recess whereby said tools are adapted to engage the work, and means operative when said tools are in work-engaging position for fixedly positioning each said carrier with respect to the work, each said tool being movably mounted on its carrier whereby it may operate on the work when the carrier is fixed with respect thereto.

3. A device of the character described comprising, in combination, a fixedly positioned, work-receiving table, guide means for predeterminedly positioning work thereon, means providing a recess in said table adjacent one edge thereof, a platform positioned in part beneath the work-receiving surface of said table and underlying said recess, a plurality of tool carriers pivotally mounted on said platform, each said carrier being provided with a roller support engaging a rail mounted on said platform, a plurality of cutting tools mounted on each said carrier, each carrier being movable into and out of position beneath said recess whereby said tools are adapted to engage the work, and means operative when said tools are in work-engaging position for fixedly positioning each said carrier with respect to the work, each said tool being movably mounted on its carrier whereby it may operate on the work when the carrier is fixed with respect thereto.

4. A device of the character described comprising, in combination, a fixedly positioned, work-receiving table, guide means for predeterminedly positioning work thereon, means providing a recess in said table adjacent one edge thereof, a platform positioned in part beneath the work-receiving surface of said table and underlying said recess, a plurality of tool carriers pivotally mounted on said platform, a plurality of cutting tools mounted on each said carrier, each carried being movable into and out of position beneath said recess whereby said tools

are adapted to engage the work, and clamps carried by each said carrier for engaging the work when the tools carried by said carrier are in work-engaging position, each said tool being movably mounted on its carrier whereby it may operate on the work when the carrier is fixed with respect thereto.

5. In a device of the character described, in combination, means providing a fixedly positioned, work-receiving surface, a plurality of abutment elements for positioning work thereon, means positioned adjacent said surface for supporting a plurality of tool carriers, at least one cutting tool mounted on and movable with each said carrier, each carrier being movable into and out of a position in which the tool carried thereby engages the work, and means operative when the tool carried by each carrier is in work-engaging position, to fixedly position the said carrier with respect to the work, each said tool being movably mounted on its carrier whereby it may operate on the work when the carrier is fixed with respect thereto.

6. In a device of the character described, in combination, means providing a fixedly positioned, work-receiving surface, a plurality of abutment elements for positioning work thereon, means positioned adjacent said surface for supporting a plurality of tool carriers, at least one cutting tool mounted on and movable with each said carrier, each carrier being movable into and out of a position in which the tool carried thereby engages the work, and clamps carried by each said carrier and adapted to engage the work when the carrier is in position for the tool carried thereby to engage the work, each said tool being movably mounted on its carrier whereby it may operate on the work when the carrier is fixed with respect thereto.

7. A device of the character described comprising, in combination, a fixedly positioned, work-receiving table, guide means for predeterminedly positioning work thereon, means providing a recess in said table adjacent one edge thereof, a platform positioned in part beneath the work-receiving surface of said table and underlying said recess, a plurality of tool carriers pivotally mounted on said platform, a drill and a mortiser mounted on each said carrier, each carrier being movable between a position in which said tools engage the work and a position removed therefrom, only one said carrier being adapted to be in work-engaging position at any one time, and locking means operative to hold that carrier in work-engaging position fixedly with respect to the work, each said tool being movably mounted on its carrier whereby it may operate on the work when the carrier is fixed with respect thereto.
